UNITED STATES PATENT OFFICE.

FRED F. BALLARD, OF HOT SPRINGS, ARKANSAS.

HEAD-CARRIED LIGHT.

1,294,752.

Specification of Letters Patent. Patented Feb. 18, 1919.

Application filed February 27, 1918. Serial No. 219,502.

To all whom it may concern:

Be it known that I, FRED F. BALLARD, a citizen of the United States, residing at Hot Springs, in the county of Garland and State of Arkansas, have invented certain new and useful Improvements in Head-Carried Lights; and I do declare the following to be a full, clear, and exact description of the invention, such as will enable others skilled in the art to which it appertains to make and use the same.

My invention has for its object to provide an extremely simple and inexpensive, yet a highly efficient and convenient light to be mounted on the head of the user through the instrumentality of a head band or other suitable head gear, the device being intended principally for automobile trouble on the road, although it is equally well adapted for use by physicians, surgeons, plumbers and other artisans requiring such a device.

With the foregoing general object in view the invention resides in the novel features of construction and unique combinations of parts to be hereinafter fully described and claimed, the descriptive matter being supplemented by the accompanying drawing which forms a part of this specification and in which:

Figure 1 is a perspective view of the invention applied;

Fig. 2 is an enlarged perspective view showing the plug which carries the lamp disconnected from the socket carried by the head gear;

Fig. 3 is a detail vertical section on the plane of the line 3-3 of Fig. 2;

Fig. 4 is a detail horizontal section on the plane of the line 4-4 of Fig. 2; and

Fig. 5 is yet another detail vertical section showing more particularly the means for holding the plug in the socket.

In the drawing above briefly described, the numeral 1 designates a support which may be in the form of a head band or any other preferred type of head gear, said support having on its front side a socket 2 in which is removably received a plug 3 from which an arm 4 extends forwardly, said arm carrying a suitable electric light 5 having a push button switch 6 for illuminating and extinguishing the same. Electric current may be supplied to the light 5 by any preferred means, but I prefer to employ the usual two-wire cable 7 leading from

either of a plurality of batteries 8 carried in suitable pockets on a belt 9.

The socket 2 is formed of a single vertically disposed sheet metal plate secured along its vertical center to the support 1 by rivets or the like 10 as seen in Fig. 3, the opposite ends of said plate being bent laterally into forwardly converging relation to form the sides 11 of the socket, the front edges of said sides extending in parallel relation as seen at 12. The plug 3 is of dove-tail shape and is received snugly between the sides 11 of the sockets, the front edge of said plug having a vertical rib 13 located between the parallel portions 12 of said sockets. The rib 13 is formed with a socket 14 in which a spring pressed detent 15 is received when the socket is in place, to hold said socket and the plug in proper relation.

The upper end of the plug 3 is preferably provided with a hook 16 whereby it may be suspended if required, and an additional hook or eye 17 is provided at the lower end of said socket to support the cable 7.

An ear 18 is formed integrally with and extends forwardly from the rib 13 of the plug 3, the rear end of the arm 4 being connected to said ear by a pivotal and frictional joint 19 of any preferred construction. The arm in question is formed of a rear section 20 which is connected to the ear 18 as shown for vertical swinging, and a front section 21 similarly connected to said rear section at 22, the section 21 being twisted between its ends at 23 so that its front end is located in a horizontal plane, said end being connected to the rear end of the light 5 by a frictional and pivotal joint 24. The three joints 19, 22 and 24 permit the light 5 to be moved into practically any required position for obtaining the best results.

The device is particularly well adapted for automobilists when changing tires or making necessary repairs on the road at night or in unlighted garages, but it will be clear that it may be used to equal advantage for numerous other purposes. Since probably the best results are obtained from the exact features shown and described, these features are preferably employed, but within the scope of the invention as claimed, numerous minor changes may well be made. Also, it is to be understood that the plug 3 may be removed from the socket 2, in which

case the device may be used as a hand lamp without the support. When so used, the hook 16 is often of great advantage since by its use the light may be supported in convenient positions for shedding its rays where necessary.

I claim:

The combination with a support adapted to be mounted on the user's head, of a vertically disposed metal plate secured at its central portion to the front of said support, the two ends of said plate being bent laterally into forwardly converging relation and then extending forwardly in parallel relation, a dove-tail block received slidably between

said converging portions of said plate and having a rib snugly received between said parallel portions, said rib having a socket in one side, a spring pressed detent mounted on said plate and engaging said socket to hold said block in place, and a light carried by said block.

In testimony whereof I have hereunto set my hand in the presence of two subscribing witnesses.

FRED F. BALLARD.
